UNITED STATES PATENT OFFICE.

ERNEST E. LINDSEY, OF SAN FRANCISCO, CALIFORNIA, ASSIGNOR OF ONE-HALF TO
JOHN H. HERRING, OF PIEDMONT, CALIFORNIA.

AUTOMATIC DOUGHNUT COOKER.

Application filed October 7, 1919. Serial No. 328,989.

To all whom it may concern:

Be it known that I, ERNEST E. LINDSEY, a citizen of the United States, residing at San Francisco, in the county of San Francisco and State of California, have invented a new and useful Automatic Doughnut Cooker, of which the following is a specification.

5 My invention relates to improvements in automatic doughnut cookers in which dough-nuts are deposited, turned over, cooked, drained and delivered ready for use, and the object of my improvements is to provide
10 mechanical means for accomplishing this work in place of the hand methods now in vogue.

I attain these objects by the mechanism illustrated in the accompanying drawing, in which

Figure 1 is a plan of the entire machine;
Figure 2 is a cross section of the machine
along the line A-A:

Figure 3 is a sectional detail along the line BB, showing the means used for turning the doughnuts:

Figure 4 is a sectional detail along the line CC, showing the means used for draining and delivering the doughnuts.

25 Similar numerals refer to similar parts
30 throughout the several views.

While uncooked doughnuts may be prepared by hand, I prefer to use a mechanical dough cutting and depositing device so placed that the doughnut is dropped at point 1 into the hot oil or fat which fills channel 2. The doughnut is carried along the channel 2 by the current of oil which at the proper time carries the doughnut against the upper inclined surface of belt 3 which is

the upper inclined surface of belt 3 which is moving in the same direction as the oil current. The doughnut is carried up by the belt and is discharged over the upper pulley on to the upper side of belt 4 which is trav-

45 selling in the opposite direction. The two belts are so spaced and speeded that the doughnut is at last discharged back into the oil in an inverted position so that the portion of the doughnut previously immersed in the oil and which has been cooked is on top and the uncooked side is in the oil for further cooking. No means are shown for driving belts 3 and 4 as any convenient combination of gears, chains, sprockets, belts and pulleys 50 may be used in which there is no novelty.

After being cast back into the oil, the doughnut is carried along channel 2 to belt 5 where it is again raised out of the oil by being forced against the upper surface of the inclined belt 5 by the oil current. The said upper surface of belt 5 is moving in the same direction as the oil current and the doughnut is carried on said belt until it is discharged over the upper pulley into any convenient receptacle. No means of driving belt 5 are shown for the same reasons as set forth in connection with belts 3 and 4. 55 60 65 70

Channel 2 is here shown with a spiral plan, but any other course may be substituted, combined of tangents, angles, and curves, the only limitations being a sufficient cross-sectional area to permit the doughnuts to pass and a sufficient length so that the time to travel the course will equal the time required to properly cook the doughnuts. A cover may be provided or the channel may be left open. The proper temperature is maintained in the oil by means of a heating device under the channel 2 shown here as a gas burner 6, though any other heating means may be employed. The hot oil or grease is caused to flow at the desired velocity along channel 2 by the circulating pump 7 and the connected piping which carries the oil from the end of channel 2 at point 8 back to point 1. The pump 7 may be driven by any convenient motor or mechanism but none is here shown. While this machine has been described as a doughnut cooking device, it will be noted that other dough products may be cooked and also that nuts or any other foods which may be treated or cooked in deep fat may be so treated or cooked in this machine, provided only that the specific gravity is not so great that the current of oil will be unable to carry said food along channel 2.

I claim:

1. In apparatus for cooking free articles in hot fluid, the combination of a receptacle for the fluid; and means for circulating the fluid and for progressing the articles over a gyratory course in the receptacle, under propulsion by the fluid, including a guide extending spirally outward from the center of the receptacle to its periphery. 100

2. A cooking apparatus comprising a receptacle or pan for a cooking fluid; means for moving the fluid in the pan; means for

guiding the articles to be cooked over a circuitous course within the pan whilst propelled by the moving fluid; and means for turning over said articles during their travel 5 through the apparatus.

3. In apparatus for cooking articles with hot fluid; the combination of a receptacle for the hot cooking fluid in which the articles to be cooked are propelled by motion of the fluid; and means in the path of travel of the articles under propulsion by the fluid for turning them over in the course of their travel, to insure cooking on both sides.

4. A cooking apparatus comprising a receptacle for containing a cooking fluid; a channel in said receptacle so disposed as to provide for the continuous circulation of the cooking fluid throughout said channel and having one portion of said channel so proportioned that articles of food may be deposited at one end of said portion of said channel into said cooking fluid and thence transported by the current of the circulating cooking fluid through said portion of said channel to the other end thereof where said articles of food are removed from the cooking fluid after having been subjected to the temperature of the cooking fluid for a period of time long enough to properly cook the said articles of food, and means in the path of travel of the articles under propulsion by the fluid for turning them over in the course of their travel.

5. A cooking apparatus comprising a receptacle for containing a cooking fluid; a channel in said receptacle so disposed as to provide for the continuous circulation of the cooking fluid throughout the said channel and having one portion of the said channel so proportioned that articles of food may be deposited at one end of said portion of said channel into said cooking fluid and thence transported by the current of the circulating cooking fluid through said portion of said channel to the other end thereof where said articles of food are removed from the cooking fluid after having been subjected to the temperature of the cooking fluid for a period of time long enough to properly cook the said articles of food; means for depositing said articles of food into said cooking fluid and means for removing said articles of food from said cooking fluid and means to cause the circulation of the cooking fluid, and means in the path of travel of the articles under propulsion by the fluid for

turning them over in the course of their travel.

6. A cooking apparatus comprising a receptacle for containing a cooking fluid; a channel in said receptacle so disposed as to provide for the continuous circulation of the cooking fluid throughout the said channel and having one portion of the said channel so proportioned that articles of food may be deposited at one end of said portion of said channel into said cooking fluid and thence transported by the current of the circulating cooking fluid part way through said portion of said channel there turned over and thence transported by the current of the circulating cooking fluid to the other end of said portion of the said channel where said articles of food are removed from the cooking fluid after having been subjected to the temperature of the cooking fluid for a period of time long enough to properly cook first one side then after being turned over to properly cook the other side of said articles of food; means for depositing said articles of food into said cooking fluid; means for turning over said articles of food; means for removing said articles of food from said cooking fluid; means to cause the circulation of the said cooking fluid; and means to heat the said cooking fluid.

7. In a cooking apparatus of the type described, the combination of heating means having a plurality of heating elements, a channel, means for circulating a fluid in said channel and for causing the circulation of fluid to transport the articles of food along the channel and cook the food and means in the path of travel of the articles under propulsion by the fluid for turning them over in the course of their travel to insure cooking on both sides.

8. In a cooking apparatus of the type described, the combination of heating means having a plurality of heating elements, a channel and means for circulating a cooking fluid in the channel to transport and cook the articles of food, said channel being arranged so that each article of food is successively subjected to heat from the different elements of the heating means and means in the path of travel of the articles under propulsion by the fluid for turning them over in the course of their travel to insure cooking on both sides.

ERNEST E. LINDSEY.
